PUMP

Glenn More and Gunnard A. Oberg, Jamestown,
N. Y., assignors to Blackstone Manufacturing
Company, Jamestown, N. Y., a corporation of
New York

Application October 3, 1932, Serial No. 635,988

2 Claims. (Cl. 308—134)

This invention relates to improvements in pumps and consists of the matters hereinafter described and more particularly pointed out in the appended claims.

5 The object of the invention is to produce a pump which is of simple and economical construction and is provided with a novel and efficient packing which will prevent leakage.

Another object of the invention is to provide a 10 pump in which adjustment of the stuffing box is automatically taken care of at all times so that there is no possibility of the pump becoming locked, as may occur where the stuffing box requires mechanical adjustment.

15 These and other objects and advantages of the invention will appear more clearly as we proceed with our specification.

In illustrating the invention, we have shown the improved pump as applied to a washing machine for draining water from the tub at the completion of a washing operation or when changing the water therein. It will be obvious, however, that this is merely one example of the use of the pump, which may be applied for draining water 25 from other containers.

In the drawings:—

Figure 1 is a view representing a washing machine in side elevation with our improved pump applied to drain the water from the bottom of the 30 tub and located in a position adjacent the motor located below the bottom of the tub.

Figure 2 is a front elevation of the pump with the bottom section of the washing machine gearing casing, by means of which casing section the 35 pump is supported. In this view the pump is shown with its drive pulley in operative engagement with the motor belt.

Figure 3 is a view similar to that of Figure 2 with the pump shown in that position which it occupies when its drive pulley is in inoperative relation with respect to the motor belt.

Figure 4 is a view representing on an enlarged scale a side elevation of the pump.

Figure 5 is a view representing a section of the 45 pump in a vertical plane through the longitudinal central axis of the pump shaft on a scale like that of Figure 4.

In Figure 6 are shown perspective views, respectively, of a combination stuffing gland and 50 bearing and a bearing sleeve, which are contained in the housing for the drive shaft of the pump.

Referring now to that embodiment of the invention illustrated in the drawings:—10 indicates a washing machine of any familiar construction, including a tub 11 standing on legs 12; 13

indicates a motor for driving the gearing of the washing machine. Said motor is mounted on a platform 14 supported on spring shock-absorbing bars 15, 15 attached to a horizontal bar rigidly supported by the legs of the tub. 17 indicates the improved pump which is supported by the gear casing of the washing machine, as shown in Figures 2 and 3, wherein 17a indicates the bottom section of said gear casing.

18 indicates the pump casing. This comprises 10 a flat circular shell 19 having an integral end wall on one side indicated at 20 and being open on the opposite side. The open side of said shell is closed by a flat plate 21 which is made integral with a centrally disposed bearing sleeve or housing 22. 23 indicates a tubular inlet pipe made integral with the wall 20 of the casing and opening laterally into the shell 19. 24 indicates a tubular discharge pipe likewise integral with the shell 19 and opening radially thereinto. The 20 plate 21 and the shell 19 are secured together by suitable bolts 21a, there being a suitable gasket disposed between the shell and said plate to make a water-tight joint.

The pump is of the familiar rotary centrifugal 25 type. 25 indicates the rotor of the pump, the same consisting of a flat disc 26 having a centrally disposed hub 27 extending laterally therefrom and curved vanes 28 also extending laterally therefrom and connected to said hub.

30 29 indicates a shaft for the rotor. Said shaft has bearing in the tubular housing 22 and has a projection 30 of reduced diameter which extends beyond the plate 21, where it is fixed within the hub 27 of the rotor. The housing 22 has a radial 35 inwardly projecting flange 31 in the plane of the disc 26, which flange loosely engages the shaft 29. The shaft 29 projects beyond the housing 22 (in a direction away from the pump casing) and has there fixed to it a pulley 32.

33 indicates a sleeve which presents a combination stuffing gland and bearing within the housing. Said sleeve is spaced laterally from the plate 21. 34 indicates a bearing sleeve at the end of the housing proximate to the pulley 32. Packing 35 is interposed about the shaft 29 between the flange 31 of the housing 22 and the nearer end of the combination stuffing gland and bearing 33. Preferably the opposed parts of the flange 31 and of the combination bearing and stuffing gland 33 are inclined away from each other so that the packing 35 is longer adjacent the shaft 29 than it is adjacent the housing 22. A coiled spring 36 is interposed about the shaft

29 between the combination bearing and stuffing gland 33 and the bearing sleeve 34.

The bearing sleeve 34 is fixed by a set screw 37 both against rotative and longitudinal movement in the housing 22. The combination stuffing gland and bearing 33 is capable of longitudinal movement in the housing 22, with the result that the coiled spring 36 holds it against the packing 35. The opposed ends of the combination stuffing gland and bearing 33 and of the bearing sleeve 34 are notched to provide radial shoulders 33a and 34a, respectively, as shown in Figure 6. Said shoulders are opposed circumferentially and are engaged by the ends of the coiled spring 36. The spring 36 is coiled in a direction opposite to that in which the shaft is designed to be driven.

Any rotation of the combination stuffing gland and bearing sleeve 33 with the shaft is resisted by the coiled spring, which is locked against rotation as a whole by the engagement of its right-hand end against the shoulder 34a of the fixed bearing sleeve 34. In addition, such rotation would tend to uncoil the spring and thus expand it radially so as to lock the spring in the housing. Thus the strain on the fixed bearing sleeve 34 due to any tendency to rotation of the combination stuffing gland and bearing 33 is reduced to a minimum.

30 In the bottom of the housing is set a pressure grease or oil cup 38 by means of which lubricant may be forced into the housing to continuously renew the supply therein. By the location of the grease or oil cup 38 intermediate the gland 33 and sleeve 34, the bearing is lubricated from the inside, and water from the pump is thus prevented from entering into the packing and into the bearing housing.

The pump casing is provided with laterally spaced, upwardly projecting apertured ears 39 by which the pump as a whole is hinged to lugs 39a depending from the bottom of the gear casing section 17a, as shown in Figures 2, 3 and 5. The pump is so located that the pulley 32 is in the plane of the belt 13a of the motor. In Figures 1 and 2 the pulley 32 is shown engaged with said belt by means of which it is driven so as to rotate the shaft 29 and operate the rotor 25 of the pump. In Figure 3 the pump is in the idle position.

50 The shaft housing 22 has an upwardly projecting apertured lug 40 to which are pivotally connected plates 41 engaged by a crank arm 42 on a horizontal rock shaft 43. Said rock shaft extends horizontally below the gear casing section 17a, which has depending lugs 43a, 43a, in which said rock shaft is rotatively mounted. Said rock shaft extends through and beyond the usual apron surrounding the gearing below the washing machine. There it is provided with a handle 60 44 for rotating the crank arm 42 to raise or lower the housing by swinging the pump as a whole on the pivotal connection of the ears 39 with the lugs

39a depending from the gear casing. By this means the pulley may be brought to engagement with the belt 13a when it is desired to operate the pump or may be moved from such engagement, as shown in Figure 3, where it is not engaged by said belt, and the pump will be idle. The bottom ends of the plates 41, in either position of the pump, engage a shoulder 40a on the pump casing at one side of their pivotal connection with the lug 40 and a coiled spring 44a connecting the crank arm 42 to the casing 17a, causes said arm to snap to either position in a familiar manner.

5 A short flexible hose 45 connects the inlet 23 of the pump to a drain in the bottom of the tub in the usual manner. A like and longer piece of hose 46 is connected to the outlet or discharge pipe 24 of the pump and its free end may be led to any suitable drain outlet for the discharge of the water from the pump.

10 The stuffing box being placed immediately adjacent to the rotor casing, the entrance of water into the shaft housing is absolutely prevented. In addition, any wear of the parts and adjustment required therefor is automatically taken up by 15 the pressure of the spring 36 which yieldingly forces the end of the combination stuffing gland and bearing 33 against the packing 35. No locking of the pump shaft may occur, since any tendency to bind the shaft for any reason whatever 20 would be prevented by the yielding of the spring.

25 We claim as our invention:

1. In combination with a rotary shaft and a housing therefor, means providing a stuffing box in said housing, including a packing, a combination stuffing gland and bearing for said shaft longitudinally movable in said housing, a bearing sleeve in said housing spaced from said gland, the opposed ends of said gland and sleeve being constructed to present shoulders facing in opposite 30 directions, and a coiled spring on said shaft interposed between said gland and sleeve and having ends engaged with said shoulders, said spring being coiled in a direction opposite to that in which said shaft is designed to rotate and its diameter approaching the inner diameter of said housing.

40 2. A rotary pump shaft packing including a housing, a bearing sleeve fixed in said housing, a combination stuffing gland and bearing spaced 45 from said fixed bearing sleeve, packing engaged with the outer end of said gland, and an expansion coiled spring interposed about said shaft between said fixed bearing sleeve and said gland, said spring approaching the inner diameter of 50 said housing but being normally free therefrom, said spring being coiled and engaged, respectively, with said fixed sleeve and gland to expand upon rotation of said gland with said shaft.

55 60 GLENN MORE.
GUNNARD A. OBERG.
